(57) CLAIM

The ornamental design for a swivel screen and attached extension handle for remote handling and drain oil narrowing stream for collecting used engine oil, as shown and described.

DESCRIPTION

FIG. 1 is a top plan of a swivel screen and attached extension handle for remote handling and drain oil narrowing stream for collecting used engine oil, showing my design;

FIG. 2 is a right side elevation view thereof;

FIG. 3 is a bottom plan view thereof;

FIG. 4 is a front elevation view thereof; and,

FIG. 5 is a rear elevation view thereof.
